DAMPER CONTROL MECHANISM

Filed June 18, 1931

UNITED STATES PATENT OFFICE

CHARLES H. ANDERSON, OF CHICAGO, ILLINOIS

DAMPER CONTROL MECHANISM

Application filed June 18, 1931. Serial No. 545,279.

More particularly this invention relates to an improved damper and control mechanism for use in the stack pipe of furnaces of boilers, or other types of heating apparatus, and especially to such a mechanism which may be operated automatically by a pressure or other control device on the apparatus.

The general object of the invention is to provide a new and improved damper mechanism which is simple in construction and may be readily installed, and which is automatically operable to run the furnace at high efficiency and cut down the fuel consumption.

Another object is to provide an improved damper mechanism adapted to be installed in the stack pipe of a furnace, and means for connecting the damper for operation by the pressure or other control means embodying a sliding connection adapted to close the damper quickly when the pressure reaches its normal value, and operable to permit the damper to remain in a substantially closed position if the pressure rises above its normal value.

Another object is to provide a new and improved damper comprising an inner disk member and a ring member surrounding said disk, together with means for adjusting said members angularly with respect to each other and for operating them in unison.

Further objects will become apparent from the following detailed description taken in connection with the accompanying drawing, in which:

Fig. 1 is an elevational view of a boiler installation showing a preferred form of the invention installed in the stack pipe of a furnace and with the damper partly closed.

Fig. 2 is a fragmentary portion of Fig. 1 showing the damper mechanism in the position it assumes when the pressure on the boiler is abnormally high, the damper being substantially closed.

Fig. 3 is a similar fragmentary view showing the damper mechanism when the pressure on the boiler is below normal, the damper being substantially wide open.

Fig. 4 is a perspective "phantom" view of the preferred form of the invention mounted in a pipe and showing the details of construction.

Fig. 5 is a detail view of one of the parts.

For purposes of disclosure, I have illustrated in the drawing and shall hereinafter describe in detail a preferred embodiment of the invention, with the understanding that I do not intend to limit the invention to the particular construction and arrangement shown, it being contemplated that various changes may be made by those skilled in the art without departing from the spirit and scope of the invention as expressed in the appended claims.

In Fig. 1 of the drawing there is shown a furnace 5 having a stack pipe 6 leading from the upper rear portion thereof. A pressure control device 7 is mounted on top of the furnace and embodies a lever 8 pivotally mounted intermediate its ends at 9 and operable by means of a rod 10 which is connected to the usual bellows device or diaphragm (not shown). An adjustable weight 11 is mounted on one end of the lever 8. The other end of the lever is connected by means of a chain 12 to a draft control door 13 and is also connected by means of a chain 14 to a control door 15 which is mounted on the rear side of the furnace, to one side of the pipe 6. The chain 14 is preferably provided with a certain amount of slack so that the door 15 will be opened at a higher pressure than that necessary to close the door 13. Thus, as illustrated in Fig. 1, wherein the pressure control lever 8 is in a position comparable to normal pressure on the boiler so that the draft door 13 has been closed, the door 15 is also closed and will not be opened until the pressure control lever has been moved by the rod 10 in a counterclockwise direction due to an increase in pressure above normal.

The damper mechanism, as illustrated most clearly in Fig. 4, comprises a horizontally extending pivotally mounted shaft or rod 16 which passes through diametrically opposite apertures in the pipe 6. One end 17 of this rod is preferably bent substantially perpendicular to the remainder of the rod so as to extend radially therefrom and provide a means or member for rotating the rod and for indicating its angular position. The damper preferably comprises an inner disk

member 18 secured nonrotatably to the rod 16 in the plane of the radially extending member 17, and an encircling ring member 19 which is rotatably mounted on the rod 16 by means of sleeves 20 and 21. These sleeves extend through the wall of the pipe 6 and are rotatable with respect thereto. Preferably an arm or member 22 is secured to the sleeve 21 and extends from the sleeve substantially in the plane of the ring member 19 so as to serve as a means for rotating the ring member relatively to the disk member and also as a means for indicating externally of the pipe, the angular position of the ring member.

15 Means is preferably provided for adjusting the disk member 18 angularly relatively to the ring member 19 and for securing the two parts of the damper in their adjusted positions relatively to each other. As illustrated herein, this means comprises a member 23 which is slidably mounted in a bore extending through the end 17 of the rod 16. The member 23 is shown herein in the form of a rod having one end 24 bent so as to extend longitudinally of the rod 16. The portion 24 is arranged to engage a pin 25 which extends radially from the sleeve 21 and has its inner end screw threaded through a tubular bushing 26, which surrounds the sleeve 21 adjacent its outer end and into clamping engagement with the sleeve 21. Thus by sliding the member 23 through the end 17 of the rod 16 the portion 24 thereof will swing the pin 25 angularly with respect to the portion 17 and thereby swing the ring member 19 angularly with respect to the disk member 18. The rod 23 may be clamped in its adjusted position by means of a nut device 27. The pin 25 may be rotated by means of a cross bar 28.

40 The damper is arranged to be operated automatically by means of the pressure control device 7 through intermediate connections which are herein illustrated as including a rod or arm 29 which extends radially from the bushing 26 and has its inner end screw threaded thereto. A weighted member 30 is preferably secured to one end of a chain 32 and slidably connected to the arm 29. As 45 illustrated herein the weighted member 30 is mounted on the arm 29 and has an eye-bolt 31 thereon connected to one end of a chain 32. The other end of the chain 32 is provided with a hook 33 so that it may be secured to any one of several links of a chain 34 which extends over roller devices 35 and 36 and has its other end secured to the front end of the lever 8 by means of a clamping device 37. In the installation disclosed in the drawing, the 50 pulley 35 is positioned substantially vertically above the axis of the damper rod 16 in order that the control mechanism will function efficiently. It has been found that by 55 positioning the pulley 35 in a vertical plane disposed a distance h from the vertical plane

through the eye of the weighted member 30 when in the dotted line position shown in Fig. 1, the operation is very successful, the distance h being made one and one-fourth inches for each foot of the vertical distance v that 70 the shaft 16 is positioned below the pulley 35.

The type of slidable connection provided between the weighted member and arm 29 is arranged to provide lost motion principally 75 during the initial movement of the weighted member downwardly from the position shown in Fig. 2 when the weighted member is lowered by action of the pressure control device 7. After the weighted member has descended a certain distance the angular movement imparted to the arm 29 becomes more in proportion to the downward movement of the weighted member 30. Oppositely, when the weighted member is raised from the position 80 shown in Fig. 3, the arm 29 is moved proportionately during the initial portion of the upward movement of the weighted member so that the lost motion between the parts occurs as the damper approaches its closed position. 85

The invention is preferably provided with a sheet metal band 40 which is adapted to fit snugly around the pipe 6 and is split and provided with outstanding lugs 41 so that it may be wrapped around the pipe 6 and then 90 clamped thereto by means of a suitable screw device 42. This band is provided with accurately cut diametrically opposite apertures for the sleeves 20 and 21. The provision of such a band is advantageous in that it permits the workmen installing the device to punch diametrically opposite holes in the pipe 6. If the punched holes should be irregular in shape, or too large, the band 40 is fitted around the pipe so that the accurately 95 finished holes therein coincide with the punched holes in the pipe. This provides finished bearings for the sleeves 20 and 21 and prevents smoke from leaking out of the punched holes in the pipe. 100

110 In installing the device the rod 16 is withdrawn from the damper members 18 and 19, and the ring member 19 is first inserted by compressing the pipe vertically a sufficient amount to bulge the sides and permit the 115 ring member 19 to be inserted and the sleeves 20 and 21 positioned in the holes in the pipe 6 and band 40.

The arm 22 is then positioned with its bifurcated portion extending into the grooves 120 45 in the sleeve 21 and the clamping nut 46 tightened against it, after which the bushing 26 is slipped over the outer end of the sleeve 21. The disk member 18 is then positioned within the ring member 19 and the rod 16 125 inserted from the right-hand end (Fig. 4). The disk member 18 has spaced lugs 47 and 47^a thereon provided with substantially circular openings through which the rod 16 passes with a snug fit. Any suitable means 130

may be provided for securing the disk member 18 non-rotatably to the rod, but preferably this means is adapted to permit the rod to be secured to the disk member either with 5 the end portion 17 parallel to the disk member or at right angles thereto to adapt the mechanism to both horizontal and vertical pipes. As illustrated herein, the inner end of the lug 47 has a square recess at 48 and 10 the rod 16 is provided with an aperture therethrough in which a pin 49 may be inserted. This pin is inserted with the rod 16 slightly withdrawn toward the right from the position shown in Fig. 4, and is sufficiently long 15 to extend diagonally across the squared recess 48 and engage non-rotatably with opposite corners thereof. It will be apparent that the rod may thereby be secured in positions disposed 90° from each other with respect to the disk member 18 and thereby enable the device to be installed either in a horizontal pipe 6, as illustrated in the drawing, or in a vertical pipe.

After the device has been installed it may 25 be adjusted to fit the particular fuel used, and the amount of draft in a particular installation by hooking the chain 32 to the chain 34 so that the parts are substantially in the position illustrated in Fig. 3, when 30 there is no fire in the furnace. Then upon building a fire the arm 29 will be moved to approximately the position illustrated in Fig. 1, before the weighted member 30 slides out from the rod 16 and permits an extended vertical movement of the weighted member with 35 a corresponding angular movement of the arm 29. At this point the boiler has perhaps one pound of steam, and the draft door 13 has closed. The door 15 still remains closed. The door 15 still remains closed 40 but, for the purpose of adjusting the damper mechanism, this door is opened approximately a half inch and then the ring member 19 (with the disk member 18) is moved toward a closed position until smoke starts coming 45 out of the door 15. The ring member 19 is then secured in this position by means of the pin 25 after which the disk member 18 is rotated in a counterclockwise direction, as illustrated in the drawing, to open the aperture 50 in the ring member until the smoke stops coming out of the door 15. The disk member 18 is then secured in this adjusted position relatively to the ring member 19 by sliding the rod 23 through the end 17 of the rod 55 16 until the portion 24 thereof abuts against the pin 25. The thumb screw 27 is then tightened against the rod 23 to secure the parts in this adjusted position.

The device is then adapted to operate automatically and when the steam on the boiler increases the weighted member 30 will slide outwardly on the arm 29 at the same time that it rotates the arm and damper secured thereto. However, it will be apparent that as 60 the arm 29 is rotated toward a vertical posi-

tion the angular movement of the damper decreases relatively to the upward movement of the weighted member 30 so that when normal steam pressure has been reached the damper is almost closed. If the pressure increases above normal, the damper will be moved toward the closed position, as illustrated in Fig. 2, which it reaches when the rod 10 of the pressure device 7 is substantially at its greatest height. 70

The invention provides an extremely simple mechanism embodying a novel damper construction, together with efficient means for actuating the damper automatically in accordance with the draft requirements of the furnace. The device may be readily installed and adjusted, and thereafter will function automatically to operate the furnace efficiently. By properly regulating the draft in accordance with the requirements, it is possible to obtain more satisfactory and uniform heating, and also a considerable saving in fuel. 80

I claim as my invention:

1. A damper mechanism comprising, in combination, a shaft adapted to be rotatably mounted in a stack pipe and having a part extending substantially radially from one end thereof, a damper comprising an inner disk secured to said shaft in the plane of said end part, and an outer ring encircling said disk and rotatably mounted on said shaft, a sleeve on said shaft secured at one end to said ring and arranged to extend outwardly through the pipe wall, a manually operable device secured to said sleeve for indicating the position of the ring and for moving the ring relatively to said shaft, a bushing on said sleeve intermediate said device and the radially extending end part of said shaft, a pin extending radially from said bushing and screw threaded therethrough so as to be operable to clamp said bushing to said sleeve, means for adjusting said shaft and the disk carried thereby angularly with respect to said sleeve and the ring secured thereto comprising a member slidably mounted in a bore extending transversely through the end part of said shaft and having its end adapted for engagement with said pin, and means for securing said member in its adjusted position, a relatively long actuating arm extending radially from said shaft and secured to said bushing, a weighted member 90 slidable upon said actuating arm, a flexible chain secured at one end to said weighted member and extending upwardly therefrom, a guide pulley stationarily mounted above said actuating rod over which said chain passes for connection to the pressure control mechanism of the boiler, said weight being positioned adjacent the damper rod when the damper is open with the actuating arm inclined downwardly, said weight, after the actuating arm is rotated to a position above 95 the horizontal, sliding outwardly on said arm 100 105 110 115 120 125 130

so as to decrease the angular movement of the damper relatively to the vertical movement of said weighted member.

2. A damper mechanism comprising, in combination, a shaft adapted to be rotatably mounted in a stack pipe and having a part extending substantially radially from one end thereof, a damper comprising an inner disk secured to said shaft in the plane of said end part, and an outer ring encircling said disk and rotatably mounted on said shaft, a sleeve on said shaft secured at one end to said ring and arranged to extend outwardly through the pipe wall, a bushing on said sleeve adjacent the radially extending end part of said shaft, a pin extending radially from said bushing and screw threaded therethrough so as to be operable to clamp said bushing to said sleeve, means for adjusting said shaft and the disk carried thereby angularly with respect to said sleeve and the ring secured thereto comprising a member adjustably mounted on the end part of said shaft and engaging said pin, a relatively long actuating arm extending radially from said shaft and secured to said bushing, a weighted member slidably connected to said actuating arm, and means connecting said weighted member to the pressure control mechanism of the boiler.
3. A damper mechanism comprising, in combination, a shaft adapted to be rotatably mounted in a stack pipe and having a part extending substantially radially from one end thereof, a two-part damper comprising a first part secured to said shaft in the plane of said end part, and a second part rotatably mounted on said shaft, a sleeve on said shaft secured at one end to the rotatably mounted part and arranged to extend outwardly through the pipe wall, a bushing on said sleeve, a pin extending radially from said bushing and screw threaded therethrough so as to be operable to clamp said bushing to said sleeve, means for adjusting said shaft and the damper part carried thereby angularly with respect to said sleeve and the damper part secured thereto comprising a member secured to and adjustable transversely on the end part of said shaft and having one end adapted for engagement with said pin, and means for securing said member in its adjusted position, a relatively long actuating rod extending radially from said shaft and secured thereto, a weighted member slidably upon said actuating rod, a flexible chain secured at one end to said weighted member and extending upwardly therefrom, and a guide pulley stationarily mounted above said actuating rod over which said chain passes for connection to the pressure control mechanism of the boiler.

4. A damper mechanism comprising, in combination, a shaft adapted to be rotatably mounted in a stack pipe and having a part extending substantially radially from one

end thereof, a damper comprising an inner disk secured to said shaft in the plane of said end part, and an outer ring encircling said disk and rotatably mounted on said shaft, a sleeve on said shaft secured at one end to said ring and arranged to extend outwardly through the pipe wall, a manually operable device secured to said sleeve for indicating the position of the ring and for moving the ring relatively to said shaft, a bushing on said sleeve intermediate said device and the radially extending end part of said shaft, a pin extending radially from said bushing and screw threaded thereto so as to be operable to clamp said bushing to said sleeve, means for adjusting said shaft and the disk carried thereby angularly with respect to said sleeve and the ring secured thereto comprising a member slidably mounted in a bore extending transversely through the end part of said shaft and having its end adapted for engagement with said pin, and means for securing said member in its adjusted position, a relatively long actuating rod extending radially from said shaft and secured to said bushing, and a lost motion connection between said rod and the pressure control mechanism of the boiler.

5. A damper mechanism comprising, in combination, a shaft adapted to be rotatably mounted in a stack pipe and having a part extending substantially radially from one end thereof, a damper comprising an inner disk secured to said shaft, and an outer ring encircling said disk and rotatably mounted on said shaft, a sleeve on said shaft secured at one end to said ring and arranged to extend outwardly through the pipe wall, a pin extending radially from said bushing and screw threaded thereto so as to be operable to clamp said bushing to said sleeve, means for adjusting said shaft and the disk carried thereby angularly with respect to said sleeve and the ring secured thereto comprising a member mounted on said end part of said shaft and adapted for engagement with said pin, a relatively long actuating rod extending radially from said shaft and secured to said bushing, and a lost motion connection between said rod and the pressure control mechanism of the boiler.

6. A damper mechanism comprising, in combination, a shaft adapted to be rotatably mounted in a stack pipe, a two-part damper comprising one-part secured to said shaft and another part rotatably mounted on said shaft, a sleeve on said shaft secured at one end to said rotatably mounted part and arranged to extend outwardly through the pipe wall, means for adjusting said shaft and the damper part carried thereby angularly with respect to said sleeve and the damper part secured thereto, an actuating arm extending from said shaft and secured thereto, and a lost motion connection between said rod and

the pressure control mechanism of the boiler.

7. A damper mechanism comprising, in combination, a shaft adapted to be rotatably mounted in a stack pipe, a damper comprising an inner disk secured to said shaft, and an outer ring encircling said disk and rotatably mounted on said shaft, a member on said shaft secured at one end to said ring and arranged to extend outwardly through the pipe wall, means for adjusting said shaft and the disk carried thereby angularly with respect to said member and the ring secured thereto, an actuating member secured to said shaft, and a lost motion connection between said actuating member and the pressure control mechanism of the boiler.

8. A damper mechanism comprising, in combination, a rotatably mounted rod, a damper comprising an inner disk member secured to said rod and an outer ring member encircling said disk member and rotatably mounted on said rod, means for adjusting said ring member angularly with respect to said disk member and for securing the members in such adjusted relation, an arm secured at one end to and extending radially from said rod, a weighted member slidably connected to said arm, and means for connecting said weighted member to an automatic control device on a furnace.

9. A damper mechanism comprising, in combination, a rotatably mounted rod, a damper comprising two parts, one of which is secured to said rod and the other rotatably mounted on said rod, means for adjusting said parts angularly with respect to each other and for securing the parts in such adjusted relation, a rod secured at one end to and extending radially from said first mentioned rod, a weighted member slidably mounted on said second rod, and means for connecting said weighted member to an automatic control device on a furnace.

10. A damper mechanism comprising, in combination, a rotatably mounted rod, a damper comprising an inner disk member and an outer ring member encircling said disk member, one of said members being detachably secured to said rod and the other rotatably mounted on said rod, means for adjusting said ring member angularly with respect to said disk member and for securing the members in such adjusted relation, a rod secured at one end to and extending radially from said first mentioned rod, a weighted member slidably mounted on said second rod, and means for connecting said weighted member to an automatic pressure control device on a furnace.

11. A damper mechanism comprising, in combination, a shaft adapted to be rotatably mounted in a stack pipe, a two-part damper comprising one part secured to said shaft and another part rotatably mounted on said shaft, a member secured at one end to said rotatably

mounted part and arranged to extend outwardly through the pipe wall, means for securing said shaft and the damper part carried thereby angularly with respect to said member and the damper part secured thereto, an actuating arm extending from said shaft, and means forming a lost motion connection between said arm and the pressure control mechanism of the boiler comprising a member actuated by the pressure control mechanism slidably connected to said arm, effective during the final portion of its movement in one direction to swing said arm, and during the initial portion of its movement in the return direction to return said arm.

In testimony whereof I have hereunto affixed my signature.
